CLAIM

The ornamental design for a camera, as shown and described.

DESCRIPTION

FIG. 1 is a first perspective view of a camera showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines represent unclaimed portions of the camera.

The diagonal lines indicate transparency.

1 Claim, 8 Drawing Sheets
